UNITED STATES PATENT OFFICE.

HERBERT B. MARBURY, OF ATLANTA, GEORGIA, ASSIGNOR TO FULTON BAG & COTTON MILLS, OF ATLANTA, GEORGIA, A CORPORATION OF GEORGIA.

TENT.

Application filed March 10, 1924. Serial No. 698,141.

Generically this invention appertains to tents but it more especially comprehends the type of tent known as camper's or automobile tent.

5 One object of the invention is to provide a tent which will take up a small ground space and will give increased head room for tents of this type.

Another object of this invention is to provide 10 a tent, the construction of which, will permit its being packed into a small space by the elimination of ridge poles and other heavy structure.

An important object is to provide foldable 15 supporting posts equipped with movable arms, the free ends of the arms and the upper ends of the posts or standards being provided with means for securing a ridge rope between the tops of the standards corresponding to the length of the tent 20 and secondary ridge ropes connecting the ends of the arms for forming the roof supporting structure of the tent.

Another important object is to provide a 25 bridle structure adapted to be secured to the upper end of the center post and to the free ends of the arms which, when operatively positioned, holds the ridge and secondary ridge ropes taut, thereby maintaining 30 the supporting posts against displacement.

A further important object of this invention is to provide an entrance door or flap structure adaptable not only as a closure 35 but also as an awning to provide shade in dry weather and as a protection to the entrance from rain in wet weather.

With these and other objects in view, which will become apparent as the description 40 proceeds, the invention resides in the construction, combination and arrangement of parts, hereinafter more fully described and claimed, and illustrated in the accompanying drawings, in which like characters 45 of reference indicate like parts throughout the several figures, of which:

Fig. 1 is a perspective view of my improved tent;

Fig. 2 is a transverse sectional view taken 50 on the line 2—2 of Fig. 1 showing one of the supporting poles in operative position;

Fig. 3 is a perspective view showing the 55 door flap extended as an awning;

Fig. 4 is a view in elevation of one of the supporting poles with arms extended, and 55 showing the lower section disengaged; and

Fig. 5 is a detail view of the ridge rope or one of the secondary ridge ropes.

In the illustrated embodiment characterizing this invention there is shown a tent 60 1 embodying a pair of supporting posts 2, and as these posts are identical, for the sake of convenience in description, only one will be described in detail.

The upper end of post 2 is provided with a perpendicular lug 3, which is adapted to project through the loop 4 in the end of ridge rope 5. On either side of supporting pole 2, spaced from the end thereof, is positioned the horizontally extending plates 70 6 secured to the said pole as at 7, and pivotally secured between the end of these plates as at 6' are the normally horizontal arms 8, the said arms being adapted to fold be on the said pole 2 when not in use. Secured to the free ends of the arms 8 are the upwardly extending lugs 9, which are adapted to engage the loop ends 4' of the secondary ridge ropes 5', as clearly shown in Fig. 1 of the drawings. 80

The two upright poles that support the tent proper are made in two sections, an upper section 2 and a lower section 2'. The two sections are joined by means of a metal sleeve 10, which is securely fastened to the lower end of the upper section 2, and which fits down snugly over the upper end of the lower section 2', this end being equipped with a metal pin 11 which fits into a bore 12 of corresponding size in the lower end 90 of the upper section, making a very substantial construction.

When the tent is erected, the lateral members 8 are extended out at either side of pole 2 in horizontal position, being held in place 95 by means of gable ropes 13, which extend down from pin 3 at the top of upper section of pole 2 to the slightly upwardly extending pins or lugs 9 in the outer ends of the said lateral arms 8. When not in use these 100 arms 8 hang down alongside of upper section 2 out of the way.

In order that supporting post 2 at either end of the tent may be secured against longitudinal or lateral displacement, a bridle 105 structure 14 is provided, embodying rope

15 with one end secured to the lug 3 in the upper end of post 2 and the other end secured to peg 16 or other suitable anchoring means, and cross rope 17 with its ends secured to the lugs 9 in the outer ends of arms 8 and also secured to rope 15 as at 18, by wire clamp 19 twisted around them, or by other suitable fastening means. It is obvious that when rope 15 is tightened around 10 anchoring element 16 the ridge and secondary ridge ropes will be taut, so that when the said ropes 15 at either end are so tightened the supporting poles will be rigidly secured against displacement.

15 The canvas covering 20 supported by the structure above described forms the roof, sides, and ends of the tent, the side walls substantially midway between the secondary ridges and the ground are provided with 20 extension flaps 21 equipped with a series of eyelets 22 adapted to receive one end of guy ropes 23, which when fastened to anchoring elements 24 secure the roof portion taut and allows the remaining canvas to be secured to 25 the ground by loops 25, thereby providing the perpendicular walls 26 of the tent. Both ends of the tent are provided with windows 27.

The end of the tent may simply be provided with the usual entrance flap structure 28, but it is preferable to provide the combined door and awning flap 29 with its upper end secured above the entrance as at 30 providing a door when in closed position 35 and an awning when elevated or extended, as clearly shown in Fig. 3 of the drawings. When thus elevated the outer or free end may be supported by a pole 31 and guy ropes 32 or in any suitable manner depending upon 40 the particular situation. By the provision of this flap 29 the entrance is protected from rain in wet weather so that ventilation may be had, and shade and ventilation are provided by its use as an awning 45 in hot weather.

It is apparent that this flap 29 may be secured over the flap 28 or that said flap 28 may be rolled back as desired. The said door or awning flap 29 when in closing position may have one or both sides secured to the end portions of the tent by securing means 33, or in any suitable manner.

It will thus be observed that I have designed a tent structure peculiarly adaptable 55 to the requirements of automobilists, providing ample head room though occupying a minimum of ground space, easily erected or collapsed, and when not in use occupying but little space, yet manufacturable at 60 a minimum cost.

Although in practice I have found that the form of my invention illustrated in the accompanying drawings and referred to in the above description, as the preferred embodiment, is the most efficient and practical;

yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. In combination, a tent embodying a cover and a collapsible supporting frame comprising spaced supporting poles carrying laterally extending arms pivotally secured thereto, cover supporting flexible elements connecting the arms of one pole with those of the other, a flexible ridge elements connecting the upper ends of the poles, a bridle embodying a flexible connection secured at its extremities to the arms and pole, respectively, said bridle being suitably anchored, a cover supported by the ridge elements, forming the roof, sides and end portions, the end portions being formed with windows and an entrance opening, and an anchoring means attachable to the sides of the said cover spaced from the lower edges for increasing the interior ground space of the said tent.

2. In a tent, including a tent pole having a cross-head, flexible ridge elements, a bridle comprising flexible connections secured to the extremities of the cross-head, and centrally to the pole, said bridle being suitably anchored.

3. In a tent, including a pair of tent poles having cross arms spaced from the upper extremities of said poles, flexible ridge elements interconnecting said poles and cross-arms, bridles comprising a strand, the upper end of which comprises three branches originating at a single point on the strand, the extremities of the branches secured, respectively, to the extremities of the cross-arms and the top of the pole at each end of the tent, said bridles being suitably anchored to effect tightening of said ridge elements.

4. In a tent, including spaced sectional tent poles having pivoted arms spaced from the upper ends of said poles forming cross-heads, lugs carried by the free extremities of said arms and poles, a flexible ridge element adapted to engage said lugs of said poles to effect interconnection of the poles, flexible secondary ridge elements adapted to effect interconnection of the extremities of said arms, said secondary ridge elements extending parallel to said first mentioned ridge element, bridles comprising three branches having flexible connections secured at their respective extremities to the lugs carried by the arms and centrally to the lugs

carried by the poles, said bridles being suitably anchored to effect tightening of said ridge elements.

5. In a tent, including spaced sectional tent poles having pivoted arms spaced from the upper ends of said poles forming cross-heads, lugs carried by the free extremities of said arms and poles, parallel flexible ridge elements adapted to engage said lugs to effect interconnection of said arms and poles, bridles comprising flexible connections secured at their extremities to the lugs carried by the poles and their respective arms, said bridles being suitably anchored, a cover adapted to be supported by said flexible ridge elements and to engage said lugs.

6. In a tent, including spaced tent poles having laterally extending arms spaced from their upper ends, flexible ridge elements interconnecting the free extremities of the arms, a flexible ridge element interconnecting the free ends of the poles, said last mentioned element being intermediate and in a higher plane than the first mentioned elements, a bridle embodying a flexible connection secured at its extremities to the arms and centrally to the pole carrying the arms, said bridles being suitably anchored to effect tightening and maintain said flexible ridge elements taut.

7. A tent body, including primary and secondary flexible ridge elements, of means for supporting and anchoring the elements at their extremities, and additional means coacting through a single point with the last mentioned means and associated with the free extremities of each of said ridge

elements to draw and maintain said elements taut.

8. A tent body, including primary and secondary flexible ridge elements, of supporting cross-heads embracing vertical and laterally extending arms, the vertical arms adapted to engage the free extremities of the primary element and the arms adapted to engage the free extremities of the secondary elements, and a bridle including three branches, the central branch being connected to the vertical arm and the side branches to the lateral arms of each pole to draw and maintain the ridge elements taut, said bridles being suitably anchored.

9. A tent body including a roof portion and a plurality of ridge elements associated therewith, of means for conjointly supporting and anchoring the elements at their extremities and the roof portion, and additional means coacting through a single point with the last mentioned means and associated with the free extremities of each of said ridge elements and the roof portion to draw and maintain said elements and roof portion taut.

10. A tent body including a roof portion and primary and secondary flexible ridge elements associated therewith, of means for supporting and anchoring the elements at their extremities and the roof at its ends, and additional means coacting through a single point with the last mentioned means and associated with the free extremities of each of said ridge elements to draw and maintain the ridge elements and roof taut.
